SAMUEL COHN, OF NEW YORK, N. Y., ASSIGNOR TO MANTLE MACHINERY & PATENTS COMPANY, OF NEW YORK, N. Y., A CORPORATION OF NEW YORK.

MANTLE-SHIRRING MACHINE.

1,164,783.

Specification of Letters Patent. Patented Dec. 21, 1915.

Application filed March 22, 1912. Serial No. 685,557.

To all whom it may concern:

Be it known that I, SAMUEL COHN, a citizen of the United States, and a resident of New York city, in the county and State of New York, have invented a new and useful Improvement in Mantle-Shirring Machines, of which the following is a full, clear, and exact description, reference being had to the accompanying drawings, forming part of this specification, in which—

Figure 1 is a sectional side elevation showing one form of machine; Fig. 2 is a top plan view of the structure shown in Fig. 1; Fig. 3 is a partial side elevation showing the parts of the machine in another position; and Fig. 4 is a cross-section on the line XIII—XIII of Fig. 1.

My invention relates to the class of shirring or sewing machines for mantles; that is, machines for plaiting the mantles and passing the gathering or shirring string therethrough.

The object of the invention is to provide a simple, cheap and effective machine of this character which is not liable to get out of order.

An important feature of the invention consists in means for securing the compacting of the mantle into plaits before it is forced over the needles, or before the needles are forced through the plaits.

In the drawings I show a form of machine provided with fixed needle mechanism although the mechanism may be used in any machine in which there is a relative movement between the plaiting means and needles.

In the form illustrated a lever 2^a is provided with the link 6^a connected to the central slide. The slide in this case consists of a bar 27 having a longitudinal slot 28. The bottom of this slot is closed by a bar or plate 29 secured to bar 27 by screws 30 and having transverse vertical slots. Through these slots in the floor of the central member extend pairs of vertical pins or uprights 31 having vertically extending slots 32 shown in Fig. 4. Through these slots 32 extend rods 33 running longitudinally of the slide and acting as guides. The vertically movable uprights or pin standards have their lower ends riding on a longitudinal cam 34 secured to the frame of the machine underneath the slide. Each upright is provided at its lower end with a

side extension 35, which extension cooperates with a cam 36 shown in Figs. 1, 3 and 4. These stationary cams 36 cause the standards to move down over the beveled end portion of the cams 34. An upright plate 37 has a flange or base portion screwed to the bar 27 near one end thereof, and an upwardly projecting pin 38 is set in the other end portion of the bar. The needle block 15^a carries a forwardly projecting rod 39 surrounded by a spring 40, which extends between the block and a pin 41, the other end of the rod having a pin 42 acting against the block. A front plate 43 is grooved to allow the passage of the pin 38 and is fixed to the front end of rod 39. Secured to the upright 18^a is a pivoted hook 44 normally held down by spring 45, this being arranged to interlatch with the pin 42 on the rod 39. The needle block is slidably carried on rods 46 having surrounding spiral springs 47, and the depending pin 48 on the needle block interlaces with a horizontally swinging hook 49 pivoted to the upright 18^a. In the operation of this form of machine, a tubular mantle is slipped on the uprights 31, which act as the central folding member. The movement of the handle 19^a through the medium of the shaft 5^a, gearing 4^a—3^a, arm 2^a and link 6^a will then cause the slide to move toward the needle block. As this movement continues, the uprights or pins 31 riding on the cam 34 will be progressively moved down and out of the fabric by the cam 36 operating on the extensions 35. As these uprights are successively moved down the fabric is formed into plaits by the cooperation of the uprights and the revolving side members 11^a which are actuated by pinions and side teeth or racks 8^a; and these plaits will be laid plait by plait against the front plate 43, each upright emerging from the fabric as the next upright approaches the contact point and is ready to hold the plaited fabric pressed between itself and the grooved plate. By the time the last upright is ready to move entirely out of the fabric, the plate 37 will be in a position to hold the plaited fabric pressed between itself and the plate 43, as shown in Fig. 3. The continued movement of the slide will then push the rod 39 back toward the needle block, compressing the surrounding spring until the pin 42 interlaces with hook 44. This

moves the fabric farther back on the needle, and it will be noted that at the time the needles enter each plait the uprights have already moved down and out. In other words, each plait as it is formed is fed onto the needles immediately after the uprights have emerged therefrom. The further movement of the slide will cause the pin 38 on the bar or slide to bear against the needle block 15^a to carry it back on its rods until the depending pin 48 interlatches with hook 49. This moves the needles back from the side members so as to expose the eyes for threading. The threading arm 20^a and threading hook 23^a are operated by the pin 21^a located in the slot 22^a.

On the return movement of the handle, the spring 25^a retracts said arm and the pin marked 50 on the handle 19^a engages hook 44, releasing the same from the pin 42 and allowing the spring 40 to come into action, thus pushing the plate 43 away from the needle block. This operation results in carrying the thread back through the fabric and pushing the mantle partly or wholly off the needles. During this action, the hook 49 is latched on the pin 48, thus holding the needle block in retracted position. The continued movement of the handle will then release hook 49 by the direct engagement of some part of the handle with the lever arm part 51 of this hook. This will allow the block and needles to return to their normal positions. The mantle may then be removed, and another mantle blank applied and the operation repeated.

The advantages of my invention result from the simplicity, ease and operation, and the machines are not liable to get out of order, the parts are comparatively few in number, and the operations are positive and effective.

Many changes may be made in the form and arrangement of the needle mechanism, the folders, the operating mechanism, etc., without departing from my invention.

I claim:

1. In a mantle shirring machine, side folders, each comprising a plurality of folding elements, a central folder between the side folders coöperating simultaneously with sets of folding elements of both the side folders to thereby form a plurality of shirrs in different portions of the material, and means for withdrawing the central folder from the side folders as the plaits are formed.

2. In a mantle shirring machine, a pair of side folders, each comprising a plurality of folding elements, and a central folder having a plurality of folding elements coöperating with both side folders simultaneously, said central folder being arranged to be withdrawn as the plaits are formed, substantially as described.

3. In mantle shirring machines, a pair of

side folders, each comprising a plurality of folding elements, a central folder coöperating with both side folders simultaneously and made in a plurality of parts, and connections arranged to remove said parts successively as the plaits are formed, substantially as described. 70

4. In mantle shirring machines, a pair of side folders, a central folder made in a plurality of parts, connections arranged to remove said parts successively as the plaits are formed, and means for holding the plaits compacted as the folder parts are successively removed; substantially as described. 75

5. In mantle shirring machines, a pair of side folders, a central folder arranged to successively form plaits and withdraw therefrom, mechanism for holding the compacted mass of plaits after such withdrawal, and mechanism for passing needles therethrough; 80 substantially as described.

6. In a mantle shirring machine, coöperating folding members, one having a path of movement with respect to the other and having relatively fixed folding elements, said relatively fixed elements successively interfitting with said other member during such movement to form folds successively in the material, and one member being also movable longitudinally with respect to the edge 90 of a fold formed thereby, to withdraw from such fold.

7. In a mantle shirring machine, coöperating folding members having a relative movement and different portions that successively 100 interfit during such movement, one of said members being rotatable, means for relatively moving the members to cause one to traverse the other and effect the rotation of said rotatable member to form folds successively in the material, and means for moving one of the members longitudinally with respect to the edge of a fold formed thereby, to withdraw it from the folded material.

8. In a mantle shirring machine, coöperating folding members that are relatively and bodily movable into and out of interfitting relation to form folds successively in the material placed between them, one of said members comprising elements that are 110 successively movable longitudinally with respect to the edge of a fold formed thereby, to withdraw from the folded material.

9. In a mantle shirring machine, coöperating folding members that are relatively 120 and bodily movable to form folds in material placed between them, means for effecting such relative bodily movement, one of said members comprising elements that are successively movable longitudinally of the 125 edges of the folds to withdraw therefrom, and means that successively operate on said elements during the relative bodily movement of the members for withdrawing said elements from the folded material. 130

10. In a mantle stirring machine, coöperating folding members having relatively back and forth bodily movement to fold material placed between them, means for effecting such movement, one of said members comprising a plurality of reciprocating folding elements, and means for successively reciprocating said elements during the relatively back and forth bodily movement of the members. 45
11. In a mantle stirring machine, a rotary folding wheel, a co-acting folding member having a plurality of folding elements co-acting with the wheel and capable of movement substantially parallel to the axis of the wheel, and means for effecting the said movement of the elements. 50
12. In a mantle stirring machine, a rotary folding wheel, a support having a movement with respect to the wheel transversely of its axis, a plurality of folding elements mounted on said support and movable therewith successively into co-action with the wheel, said elements also having a movement on the support to withdraw them from the folds, and means for effecting the latter movement of the elements on the support. 55
13. In a mantle stirring machine, a central former comprising a support, a plurality of folding elements mounted thereon, a pair of spaced side folding members successively coöperating with the central elements to form folds in material placed on the latter, means for effecting a relative bodily movement with the side and center members, and means for successively withdrawing the elements of the central member from the folds after their formation. 60
14. In a mantle stirring machine, a central member comprising a reciprocating support, a plurality of folding elements slidably mounted on the support and movable therewith, opposite folding wheels co-acting with the elements, said elements being mounted substantially parallel to the axes of the wheels, and cams engaging the elements to effect their reciprocating movement. 65
15. In a mantle stirring machine, a folding member comprising spaced elements, a rotatable coöperating folding member having portions movable between the elements to the first member transversely thereof, said second member traversing the first member to form folds successively in the material, means for relatively moving the members and causing the rotation of the second member to cause the said portions of the second member to be thrust transversely between the elements of the first member, and means for moving the elements of the first member longitudinally of the folds to withdraw them from the folds formed upon them. 70
16. In a mantle stirring machine, a folding member comprising spaced elements, a rotatable folding member coöperating therewith to fold the fabric upon said elements, and means for withdrawing the elements of the first member from the folds after they have been formed thereupon by the rotatable member. 75

In testimony whereof, I have hereunto set my hand.

SAMUEL COHN.
